WRAPPED PACKAGE

Stanley R. Howard, Milton, Mass., assignor to
Pneumatic Scale Corporation, Limited, Quincy,
Mass., a corporation of Massachusetts

Application August 3, 1934, Serial No. 738,258

2 Claims. (Cl. 229—87)

This invention relates to a wrapped package, and more particularly to a tight-wrapped moisture-resisting package. The object of the invention is to provide a 5 novel and highly efficient moisture-resisting tight-wrapped package, possessing characteristics which render the package commercially suitable for the packaging of those materials which heretofore presented serious difficulty on account 10 of their tendency to absorb moisture.

With this general object in view and such others as may hereinafter appear, the invention consists in the moisture-resisting tight-wrapped package hereinafter described and particularly 15 defined in the claims at the end of this specification.

In the drawing illustrating the preferred embodiment of the invention, Fig. 1 is a perspective of the moisture-resisting tight-wrapped package; 20 Fig. 2 is a cross-section on the line 2—2 of Fig. 1; Fig. 3 is a detail illustrating one form of suitable apparatus for the application of paraffin to one surface only of the wrapper; Fig. 4 is a detail of the mechanism for applying a separate layer of 25 adhesive to the paraffin layer; and Figs. 5 and 6 are views in section and in plan, respectively, of a modified form of the wrapped package and the wrapper therefor.

In general, the present invention contemplates 30 a moisture-resisting tight-wrapped package comprising a package and a wrapper therefor. The wrapper is provided upon its inner surface with a layer of wax, preferably paraffin, although if found desirable other suitable moisture-resisting 35 materials may be used. The outer surface of the wrapper is wax-free and may be provided with printing thereon. The wrapper is wrapped about the package and adhesively affixed to all surfaces thereof, producing a tight-wrapped package, 40 by an interposed layer of an adhesive capable of bonding both to the paraffin or other wax coating and also to the body of the package.

In the drawing which illustrates the preferred 45 embodiment of the invention, 10 represents a package which may comprise any of the usual forms of packages now employed in the packaging of various commodities. The package 10 after having been filled with the commodity 11 and 50 closed is wrapped with a wrapper 12. The wrapper 12 is provided upon its inner surface only with a layer 14 of wax, preferably paraffin, leaving the outer surface 15 of the wrapper wax-free and in a condition most suitable for the reception 55 of the printed matter 16 which is usually

placed upon the outer surfaces of all wrapped packages.

The wrapper 12 is in accordance with the present invention adhesively affixed to the entire surface of the package, both to the side panels 5 and ends thereof, by a separate layer of an adhesive capable of bonding both to the paraffin layer 14 and to the surface of the package itself to thereby form a tightly wrapped and highly moisture-resisting package. In practice I prefer 10 to utilize paraffin as the coating 14 for the inner surface of the wrapper, and have experienced good results in securing the desired adhesion of the paraffin layer 14 to the package by an adhesive having latex as a base. Various com- 15 mercial forms of latex adhesives are now available upon the market and such adhesive materials may be successfully used to effect the adherence of the paraffin layer to the package.

In producing the paraffin-coated wrapper with 20 the paraffin layer on one surface only thereof, various known methods of coating may be employed, and in Fig. 3 I have illustrated one form of apparatus suitable for this purpose in which 25 20 represents a paraffin-applying roll arranged to run in a heated bath 22 of paraffin to apply the layer of paraffin to the under surface of the wrapper while the upper surface of the wrapper is chilled by a chilled roll 24, thereby 30 congealing the paraffin before the latter has had an opportunity to reach the upper and outer surface of the wrapper. The adhesive may be applied to either the package or the wrapper, and in Fig. 4 I have illustrated a conventional 35 form of apparatus for applying the adhesive to the paraffin surface of the paraffin coated wrapper after the latter has passed through the apparatus shown in Fig. 3. This apparatus may comprise a pair of rolls 30, 31, and a film of the adhesive is supplied to the lower roll 31 to be 40 applied to the wrapper, from a bath 32 by a distributing roll 33 and transfer roll 34.

For some purposes it may be preferred to construct the wrapped package by wrapping about the package a wrapper having a paraffin coating 45 40 on the inner surface only thereof so as to provide the wrapped package with a wax-free outer surface and by rendering the paraffin coating 40 sufficiently adhesive by the application of heat to the wrapped package and preferably during the wrapping thereof so that the wrapper 42 may be adhesively affixed to the entire surface of the package by the single paraffin coating 40. In order to form a most satisfactory side seam, the wrapper 42 is preferably provided with a wax- 55

free strip 44, as shown in Fig. 6, along one marginal edge thereof, thereby enabling the paraffin coatings to be brought into abutment, as illustrated in Fig. 5, in the formation of the side seam of the wrapped package. In order to form the side seam, a strip 46 of glue or other adhesive may be utilized to cause the adherence of the wax-free overlapping contacting portions of the wrapper.

- 10 From the description thus far it will be observed that in accordance with the present invention an efficient and commercial form of moisture-resisting package is produced in which the wrapper is tight-wrapped about the package 15 and the outer surface of the package is preserved in a dry condition most suitable for the reception of printing, and enabling a most attractive and yet highly efficient moisture-resisting package to be produced in an economical manner.
- 15 While it is preferred to utilize a wax, preferably paraffin, as the water-proof layer, other moisture-resisting materials may be used if found advantageous, and as used herein the term "wax" is intended to include any such material.
- 20 Having thus described the invention, what is claimed is:—

1. As a new article of manufacture, a moisture-

resisting tight-wrapped package comprising a package, a wrapper therefor having a wax-free outer surface and a wax coating covering the entire inner surface with the exception of one marginal edge thereof for forming the side seam, 5 the wax coating being bonded to both the entire surface of the package and to the entire surface of the wrapper in contact therewith, the marginal portions of the wrapper overlapping to form the side seam and having the adjacent surfaces of 10 the overlapped portions wax-free and adhesively secured together.

2. As a new article of manufacture, a moisture-resisting tight-wrapped package comprising a package, a wrapper therefor having a wax-free 15 outer surface and a wax coating covering its inner surface with the exception of one marginal edge thereof, said wax coating being bonded to both the entire surface of the package and the entire surface of the wrapper in contact therewith, said package being wrapped with the marginal portions of the wrapper overlapping to form the side seam and to cause the marginal portions of the wax coating upon the inner surface of the wrapper to substantially abut one another. 25

STANLEY R. HOWARD.
